UNITED STATES PATENT OFFICE.

DAVID G. BRANDT, OF WESTFIELD, NEW JERSEY, ASSIGNOR, BY MESNE ASSIGNMENTS, TO HEAT TREATING COMPANY, OF NEW YORK, N. Y., A CORPORATION OF DELAWARE.

METHOD OF AND APPARATUS FOR DISTILLING AND FRACTIONATING OIL.

Application filed April 8, 1921. Serial No. 459,678.

This invention relates to the distillation of liquid mixtures, and more particularly to a process of and apparatus for fractionally distilling petroleum oil.

5 Crude petroleum oil is a common example of a liquid which consists of a mixture of a large number of liquid constituents that may be separated by distillation. The principal products obtained from petroleum distillations are products which are composed of groups of liquid hydrocarbons that are roughly grouped together, in accordance with the initial and final boiling points of the constituents in each group.

15 Most of the crude oil distillation is carried out by an intermittent process in which vapors are slowly driven off from a body of oil, the vapors condensed, and the condensates within a predetermined boiling point range 20 separately collected. These condensates, however, are not suitable for commercial uses but must be chemically purified and redistilled several times to secure the proper boiling point and the gravity for each fraction to 25 prepare them for commercial use.

By a more recent process oil is fractionally distilled by being passed in succession through a series of cylindrical stills. The stills in the series are maintained at progressively higher 30 temperatures and a distinct fraction is removed from each still. These fractions, however, are very rough cuts and must be chemically purified and redistilled several times to prepare them for commercial use.

35 In none of the oil distilling processes in commercial use has there been any attempt to obtain products having sharply defined boiling point and gravity limits in the first distillation, which would be suitable for commercial uses after the products have been 40 chemically treated.

One object of the present invention is to provide a process of and apparatus for continuously distilling a liquid mixture such as 45 petroleum oil by which approximately the entire range of fractions in the oil may be simultaneously separated within sharply defined limits in a single operation.

The distillation processes in common use 50 employ very inefficient heating methods and also lose enormous quantities of heat in condensing the vapors and cooling the condensates. This entails a large heat loss and re-

quires the use of large quantities of water for cooling purposes. Further, a long continued heating of oil in a large body to progressively higher temperatures tends to overheat and to decompose the oil to cause losses due to the formation of tar and unsaturated compounds and incondensable gases.

In distilling oil in accordance with the present invention, the incoming oil for distillation is preheated in acting as a cooling medium to condense the vapor fractions being formed, and to absorb the sensible heat of the condensates. The heat interchanged between the vapor and the condensates and the oil, supplies a large portion of the heat necessary for vaporizing the oil. At the same time a heat transferring gas is passed through the oil in parallel current with the vapors, and this gas assists in supplying the heat of the vaporization of the oil, while maintaining partial pressures in the distillation chamber, which materially reduce the boiling points of the vapor fractions.

With this in view another object of the invention is to provide a process of and apparatus for distilling petroleum by which fractional distillation may be carried out with a minimum consumption and loss of heat.

Another object of the invention is to provide a process of and apparatus for fractionally distilling oil at temperatures substantially below the normal atmospheric pressure 85 boiling temperatures, whereby long continued high temperature heating of the oil may be avoided and the formation of a large amount of unsaturated compounds and fixed gases may be avoided.

With these and other objects in view, the invention consists in the improved process of and apparatus for distilling oil hereinafter described and particularly defined in the claims.

The various features of the invention are illustrated in the accompanying drawings in which Fig. 1 is a view in front elevation of an oil distilling unit embodying the preferred form of the invention.

Fig. 2 is a perspective view in front elevation diagrammatically illustrating the construction and arrangement of the fractionating chambers of the distilling unit;

Fig. 3 is a vertical sectional view of the 105 fractionating chambers of the distilling unit;

Fig. 4 is a vertical sectional view of the fractionating chambers taken on the line 4—4 of Fig. 3, and

Fig. 5 is a plan view with parts broken away 5 of the distilling unit shown in Fig. 1.

The process embodying the preferred form of the invention may be briefly outlined as follows:

Oil which is preferably a crude oil or a 10 crude oil distillate, is passed by gravity downwardly in succession through a series of vaporizing chambers, and then conducted into a heating still. A specific oil fraction is vaporized in the still and in each chamber and the 15 vapor fraction is then passed upwardly into a condenser in the chamber, next above that chamber in which the vapor is formed, to be condensed by the cooler oil in this chamber. To maintain progressively increasing temperatures 20 in the various chambers from the top toward the bottom of the fractionating column, three distinct heating means are employed. First, a gas is circulated in a closed cycle through the heating still and then through the 25 chambers in succession in a path countercurrent to the path of the flow of the oil through the chambers and still. The gas is preheated before entering the still and then passes from the still, together with the vapors formed 30 therein into the condenser of the lowermost chamber of the fractionating column. After passing through the condenser the gas is bubbled through the oil in the same chamber in which the condenser is in contact with the 35 oil being treated and then flows through connections into the condenser of the next higher chamber, and so on through the entire fractionating column. In this way the sensible heat of the gas is gradually absorbed by the 40 oil in the various chambers.

The second means of maintaining the temperatures in the various chambers consists in mixing the vapors formed in the still and in each chamber with the heat transferring gas, and passing the vapors into the condenser in the chamber next above that in which the vapor is formed. The temperature differential between the oil in adjacent chambers 45 serves to condense the greatest portion of the vapors passing through the condenser, and thereby the heat of vaporization, or heat of condensation of the vapors is imparted to the oil to raise its temperature or vaporize a 50 lower boiling point fraction.

The third means of maintaining the progressive gradation in temperatures in the 55 chambers consists in collecting the residue from the still and the condensates formed in the chambers, and circulating them in separate circuits upwardly through the fractionating column in a path countercurrent to the advance of the oil through the fractionating column. By this means the sensible heat of the residue and the condensates is imparted to 60 the oil being distilled.

By the three forms of heating means it will be noted that the high temperature gas, the high temperature vapors, the high temperature residue and the high temperature condensates are brought into intimate heat 70 transferring relationship with the oil which needs to be vaporized at a high temperature. These high temperature media are therefore available at the place where the high temperature is needed. As the gas, residue, and condensates advance together upwardly through the fractionating column, they are all reduced to substantially the same temperature 75 and the temperature is gradually reduced until they are discharged from the fractionating column at substantially the same temperature 80 as that of the incoming oil.

To carry out the process above referred to in the apparatus shown in the drawings, crude oil from storage is received through a 85 pipe 10, (Fig. 1) and forced by means of a pump 12 through a pipe 14 into an upper chamber 16 (Fig. 4) of a fractionating column 18. From the chamber 16 the oil overflows by gravity and passes downwardly 90 in succession through chambers 20, 22, 24, 26 and 28, formed in the column 18 by means of transverse partitions 30. The oil enters the chamber 16 through the pipe 14 at the bottom of the chamber and overflows from the chamber 16 through a pipe 32, which is connected at its upper end with the upper portion of the chamber 16 and at its lower end with the bottom of the chamber 20. The oil overflows from the chambers 20 to 28 inclusive through 95 overflow pipes 34 having a construction the same as the construction of the overflow pipe 32. The upper ends of the overflow pipes 32 and 34 are connected to the chambers a short distance below the partitions 30, to provide a 100 space in the upper part of each chamber in which the vapors formed in the chamber may be collected in order to be passed upwardly into the next or preceding chambers to be 105 condensed. The oil which is not vaporized in the bottom or last chamber 28 of the fractionating column flows out of the chamber through a pipe 36, and is conducted into the bottom of a heating still 38 (Figs. 1 and 5). In the still 38 the oil is reduced to any desired 110 gravity to form a residue which ordinarily 115 would be classed as a fuel oil or cylinder stock.

To assist in maintaining a distinct differential in the temperatures of the oil in any 120 two adjacent vaporizing chambers, and also to assist in vaporizing the oil at subnormal temperatures, a gas is circulated through the still and chambers in a closed cycle. To this end gas which preferably consists of a gas 125 formed in distillation or a natural gas is drawn in through a pipe 40 by a pump 42, (Figs. 1 and 5) and forced through a pipe 44 into a heating coil 46, located within the exhaust flue 48 of the heating still furnace 130

50. After passing through coil 46 the pre-heated gas enters the still 38 through a pipe 52 and is distributed throughout the body of the oil in the still by means of a series of per-
 5 forated distributing pipes 54. The gas leaving the pipes 54 bubbles upwardly through the oil and is collected in the upper part of the still, together with any vapors formed in the still. The vapors formed in the still
 10 are absorbed or mixed with the gas and the gas-vapor mixture is then conducted through a pipe 56 into a condenser 58 positioned in the chamber 28 of the fractionating column 18. The condenser 58 consists of a manifold 60, (Figs. 2 and 3) positioned on the outside of the front end of the column, a manifold 62 positioned within the column, and a series of tubes 64 connected between the manifolds 60 and 62. The manifold 60 is provided with
 15 a partition 66 which divides it into an inlet section and an outlet section. The gas-vapor mixture from the still flows into the inlet section of the manifold 60 through the pipe 56, then passes through approximately
 20 half of the tubes 64 to the manifold 62 and returns to the outlet section of the manifold 60 through the remaining tubes 64. From the outlet section of the manifold the gas, together with any uncondensed vapors
 25 passes through an inverted U tube 68 into a distributor 70, positioned in the bottom of the chamber 28. The distributor 70 consists of an inverted pan having a series of holes covering its bottom and arranged to dis-
 30 tribute the gas-vapor mixtures throughout the body of oil within the chamber 28. The holes in the distributor are so designed to force the gas to pass upwardly into the oil and to prevent the oil from flowing down-
 35 wardly into the pan while the fractionating column is in operation. The gas-vapor mixture passes upwardly through the chamber 28 in the form of fine bubbles to impart its heat to the oil, and assist in vaporizing the oil within the chamber. Any vapor formed in the chamber is mixed with the gas, and the gas-vapor mixture collects in the top of the chamber from where it is withdrawn through a collecting pipe 72. The pipe 72
 40 passes outwardly through the front end of the fractionating column and is connected with an inlet section of a manifold 74 of a condenser 76 mounted within the chamber 26. The condenser 76 has the same construction as the condenser 58 and acts to conduct the gas-vapor mixture in a forward and return path through the chamber 26. The gas-vapor mixture leaves the condenser through an inverted U pipe 78 and passes into a dis-
 45 tributor 80 mounted in the bottom of chamber 26. The U pipe 78 and the distributor 80 have the same construction as the pipe 68 and the distributor 70, respectively. In a like manner the gas passes from the chamber
 50 65 26 upwardly through the condensers 82, 84, 86 and 88 positioned within the chambers 24, 22, 20 and 16 respectively. The gas collecting in the upper portion of the chamber 16 is led out through a vapor collecting pipe 90 and passes through a condensing coil 92, positioned within a condenser box 94 mounted on the top of the fractionating column 18. Any vapors which are condensed in the coil 92 are held back by a U tube 96 and are removed from the condenser through a trap 98. The gas and uncondensable vapors passing through the U tube 96 flow through a pipe 100 which is connected to the gas pipe 40 leading to the pump 42. A valve outlet 102 is provided in the pipe 100 by which excess gas which is accumulated in the distilling operation may be continuously or intermittently removed from the closed cycle in which the gas is circulated.

The sensible heat of the liquid residue 85 from the still 38 and the latent heat and sensible heat of the condensates collected in each of the chambers is imparted to the oil undergoing distillation, to assist in distilling the oil with a minimum expenditure of 90 heat. To accomplish this the gas introduced into the still by the pump 42 is maintained under sufficient pressures, so that the residue from the still will overflow through a pipe 104 to a trap 106, and be forced from the 95 trap through a separate circuit 108 upwardly through each of the chambers of the fractionating tower. The circuit 108, see Figs. 1, 2, 3 and 4, consists of a coil 110 within each 100 of the chambers and connecting pipes 112, connecting the coils of the respective chambers. The path of the circuit through chamber 26 may be modified by means of a short-circuit tube 114, which is connected between the pipe 112 and the last tube of the coil 105 110. Valves 116 and 118 are provided respectively in the pipes 114 and 112, whereby the volume and path of the residue flowing through the chamber 26 may be varied so that a part will flow through the entire coil 110, or all or a part may be by-passed to the last tube of the coil 110.

The condensate which is formed in the condenser 58 is held back by the U tube 68 and passes into a trap 120 from which it is forced 115 by the pressure in the chamber through a condensate circuit 122, passing through each of the chambers above the chamber 26. The circuit 122 has a construction similar to the circuit 108, being provided with a coil in 120 each chamber and with connecting pipes between the coils. A short-circuit pipe 124 and valves 126 and 128 are provided by which the path of flow of the condensate may be varied in the coil within the chamber 24. The condensates from the chambers 24, 22, 20 and 16 are removed from their respective condensers 82, 84, 86 and 88 in the same manner that condensate is removed from the condenser 58. These condensates are passed respectively in- 130

to traps 130, 132, 134, 136 and 138, which are connected respectively to the inverted U pipes for each of the condensers within their chambers 24—16. The traps 130 to 136, inclusive, 5 are connected respectively with condensate circuits 140, 142, 144 and 146, each circuit leading the condensate through all of the chambers above or preceding the chamber in which the condensate is formed. The condensate from trap 138 is removed through 10 pipe 148 to a receiving house.

By this construction it will be noted that each chamber contains a condensate circuit coil for each chamber succeeding it or located below it, as well as a circuit coil for the residue from the still. The pressure maintained by the gas circuit in each of the chambers is sufficient to force the condensate from the respective chambers upwardly through 15 the fractioning column. The condensates preferably may be discharged through pipes 149 passing through the rear end of the chamber 16, see Figs. 1 and 3, from which they may pass to a receiving house and the storage tanks. It may be desirable to remove the 20 high cold test cuts from chamber 20 or a chamber having a higher temperature than the chamber 16. Condensates may be taken out of chamber 20 through pipes 151. When 25 the vapors are passing through the condensers in the various chambers, those vapors which are condensable at the temperature of the oil within the chambers will be separated and any uncondensed vapors will be bubbled through 30 the oil in that chamber to pass to preceding chamber having cooler oil.

By the separate condensate and residue circuits in the various chambers approximately 40 all of the sensible heat in the condensates and residue is returned to the incoming oil. The condensates form a very large proportion of the oil originally entering for distillation, and therefore if the sensible heat in these condensates is lost, a very large portion of the 45 heat required for distillation is lost to the process. By the apparatus outlined above the sensible heat of the condensates and the residue is effectively returned to the oil undergoing distillation.

50 The construction of the fractioning tower permits a comparatively large volume of the oil to be handled with a relatively small apparatus. By having a series of chambers separated from one another by partitions, there is no radiation loss except at the sides of the column. Further, a heat transfer is maintained between the partitions to assist in effecting distillation.

60 When the gas is conducted through the condensers of each chamber under pressure, it is not necessary that the condensers should be so perfectly constructed as to prevent all leaks, because the gas pressure within the condensers is slightly higher than the pressure of the oil in the chambers surrounding

the condenser, and, therefore, any leakage of the condenser will allow gas to flow from the condenser into the oil. This leakage will not interfere in any way with the operation of the still.

With the process of an apparatus for distilling oil outlined above it will be noted that approximately all of the heat of the vaporization of the oil fractions, and approximately all of the sensible heat of the condensates will 70 be returned to the process. The only heat that will be needed to be supplied to the process will be that which will be required to provide for radiation losses, that required to maintain the temperature differential between the oil in adjacent chambers, and the heat of vaporization of the last fraction of the oil. The use of a gas circuit permits the oil to be vaporized at comparatively lower temperatures, so that there is no danger of 75 scorching, burning or cracking the oils, and the formation of fixed gases is reduced to a minimum. Further, the gas circuit furnishes an ideal medium by which the heat may be transferred to the oil, and the oil kept in active agitation to assist the heat transfer between the oil, condensates and the vapors. One distinct feature of the process resides in the fact that a selective condensation and a 80 selective evaporation take place in each 85 chamber. By this means fractions of a much closer boiling point range may be recovered 90 than in any process heretofore used.

95 In each of the chambers a heat balance is maintained. The volume of vapors passing 100 through the condenser together with the volume of condensates and the residue passing through the separate circuits in any one chamber at any time is substantially equal to the amount of oil flowing through each 105 chamber. Further, the heat capacity of the vapor, condensates, and the residue in one chamber is substantially equal to the heat capacity of the oil passing that chamber, and therefore the transfer of heat between the oil 110 and vapors, residue and condensates will maintain an effective temperature balance. Also, by maintaining this relation between the vapors, condensates, residue and the oil, 115 a sufficient quantity of high temperature heat is available in each chamber to vaporize the desired fraction.

120 With different characters of oils different quantities of fractions within a definite temperature range may be recovered. Therefore, if the temperature differential between the various chambers were comparatively large, some of the chambers would have to act to condense practically all of the vapors, 125 and the other chambers would condense only a small amount of the vapors. By having the condensate circuits arranged so that the path of flow of the circuit through any one or more of the chambers may be varied, distinct temperature differentials may be main- 130

tained in each chamber, and the fractionation may be so controlled that the proper proportion of vapors may be formed and condensed in each chamber. By varying the volume 5 of condensate passing through the various chambers also, a heat balance may be maintained, regardless of variations in the heats of vaporization of the different products and variations of the specific heats of the different products.

In the fractionating tower shown in the drawings, only six vaporizing chambers are shown. This showing is merely for illustrative purposes and for the usual petroleum 15 distillation, more than six chambers would be used. In any case, however, the number of the chambers will depend upon the character of the fractions which it is desired to separate, and upon the character of the oil.

20 Although the process has been particularly described in conjunction with the distillation of crude petroleum oil, it will be obvious that the process is not limited to petroleum distillation, but may be readily 25 adapted for the distillation of practically any liquid mixtures. The process lends itself readily for the distillation of coal tar oils and petroleum distillates. The process and apparatus illustrated and described 30 above are particularly adapted for distilling low gravity crude oil, such as Mexican and California crude petroleum, because by the use of the gas circuit low temperatures may be maintained and the viscosity of the oil 35 may be controlled to allow the oil to circulate readily and flow through the still.

The preferred form of the invention having been thus described, what is claimed as new is:

40 1. A process of fractionally distilling liquid mixtures, comprising passing a liquid mixture through a series of zones maintained at progressively higher temperatures, vaporizing successive portions of the mixture in said zones, fractionally condensing said vapors as formed by a heat interchange with said liquid in preceding cooler zones, and reducing all of said condensates to substantially the temperature of the incoming liquid mixture by a heat transfer with the liquid in the various zones.

55 2. A process of fractionally distilling liquid mixtures, comprising passing a liquid mixture through a series of zones maintained at progressively higher temperatures, vaporizing successive portions of the liquid in said zones, fractionally condensing said vapors as formed by a heat interchange with said liquid advancing toward the zone in which the vapor is formed, collecting the condensates formed in the zones, and passing the remaining vapors into scrubbing relation with said liquid having approximately the temperature of said remaining vapors, and gradually cooling 60 the condensates by passing them in heat

transferring relation to but out of contact with said liquid advancing toward the zones of higher temperature whereby substantially all of the sensible heat is absorbed from said condensates.

70 3. A process of fractionally distilling hydrocarbon oils, comprising passing oil through a series of zones of progressively increasing temperatures, vaporizing successive portions of the oil in the zones, removing 75 vapors formed in the zones and passing them through preceding cooler zones in heat interchanging relation to but out of contact with the oil in the said cooler zones, to immediately condense portions of them, passing the condensates through the zones in heat interchange relation to but out of contact with the oil, and controlling the flow of the vapors and condensates in the zones so that the heat capacities of the constituents between which the heat is transferred in any one zone are approximately equal.

80 4. A process of fractionally distilling oils, comprising passing the oil to be distilled through a series of zones, controlling the 85 temperatures of the zones to effect a selective evaporation in each zone with a gradually increasing temperature, passing the vapors formed through but out of contact with the oil in preceding zones to partially condense 90 them, scrubbing vapors uncondensed in one zone with oil in the same zone, and controlling the volume of condensates in the various zones to effect a selective condensation in each zone.

95 5. A process of fractionally distilling hydrocarbon oils, comprising passing oil through a series of zones of progressively increasing temperatures, vaporizing successive 100 portions of said oil in the zones, removing vapors formed in the zones and passing them through preceding cooler zones in heat interchanging relation to but out of contact with the said oil in the said cooler zones to condense portions of them immediately, passing the condensates through the zones of lower temperature than said condensates in heat interchanging relation to but out of contact with the said oil, and varying the circulation of 105 the said condensates through one or more of the said zones to control the boiling point of 110 the said condensates condensed in the zones.

115 6. A process of fractionally distilling hydrocarbon oils, comprising advancing oil through a series of zones of progressively increasing temperatures and thereby vaporizing portions of said oil, passing a heating gas through said zones in a path countercurrent to the path of the advance of the oil through the zones, fractionally condensing portions of 120 vapors formed in the zones by a heat transfer with oil in zones preceding those in which the vapors are formed, and separately passing the condensates in heat transferring relation to oil in the zones to reduce the 125 condensates.

densates to approximately the temperature of the incoming oil.

7. A process of fractionally distilling hydrocarbon oils, comprising passing oil through a series of distinct heating zones having progressively higher temperatures, leading oil from the highest temperature zone to a heating still, conducting a preheated gas through the still and zones in a path counter-current to the path of the flow of oil through the still and zones, separating vapors from the oil in the zones, condensing vapors by a heat interchange with oil in the preceding cooler zones, and passing the condensates through the zones in a path countercurrent to the path of the flow of the oil, while they are maintained separately and in heat transferring relation to the oil.

8. A process of fractionally distilling hydrocarbon oils, comprising passing oil through a series of distinct heating zones having progressively higher temperatures, leading oil from the highest temperature zone to a heating still, conducting a heat carrying gas through the still and zones in a path countercurrent to the path of flow of the oil therein, separating vapors from the oil in each of said zones and fractionally condensing them in other of the said zones from the one in which they were formed, and substantially absorbing the latent heat of the vapors, and the sensible heat of the condensates in the oil being treated within the said zones.

9. A process of fractionally distilling hydrocarbon oils comprising passing oil to be distilled through a series of zones maintained at successively higher temperatures and then into a still, heating the oil in the still to produce vapors therefrom, passing a heated gas through the oil in said still, conducting said gas and vapors from said still through said zones in a path countercurrent to the flow of oil therethrough whereby portions of said oil are vaporized and portions of said vapors are condensed, and heating the oil in said zones by passing the condensate formed in each zone through the preceding zones of the series.

10. A process of fractionally distilling hydrocarbon oil comprising passing oil through a series of zones maintained at progressively higher vaporizing temperatures, passing the vapors formed in each zone into heat transfer relation but out of direct contact with liquid oil in the preceding cooler zones whereby a series of condensates is produced, and heating the oil flowing from zone to zone by the condensates formed in the zones of higher temperature.

11. A process of fractionally distilling hydrocarbon oils, comprising passing oil downwardly through a series of zones maintained at progressively higher temperatures, vaporizing successive portions of oil in said zones, condensing the vapors by conducting them

through zones preceding the zones in which they are formed in a heat transferring relation to but out of contact with the oil in the zones, separating the condensates from the vapors, and maintaining sufficient pressure in the zones to force the condensates in separate circuits upwardly through the zones.

12. A process of fractionally distilling hydrocarbon oils, comprising passing oil downwardly through a series of zones maintained at progressively higher temperatures, vaporizing successive portions of oil in said zones, passing a gas upwardly through the zones in succession, mixing the vapors with the gas and passing the mixture in heat transferring relation to but out of contact with oil in the preceding zones, separating a condensate from the gas-vapor mixture in each zone, and maintaining sufficient pressure in the zones to force the condensates in separate passages upwardly through the zones preceding those in which the condensates are separated.

13. A process of fractionally distilling hydrocarbon oils, comprising passing oil in succession through a series of zones maintained at progressively higher temperatures, leading oil from the zone of highest temperature to a heating still, mixing vapors as formed in the still and zones with a heat transferring gas and passing the gas-vapor mixture through zones in a path countercurrent to the flow of oil through the zones, condensing vapors from the zones by heat transfer with the oil in preceding zones and conducting the oil residue from the still and condensates from individual ones of said zones through other of said zones in a path countercurrent to the flow of oil in the said zones while maintaining said condensates and residue in heat transferring relation to but out of contact with the oil in the zones.

14. A distilling apparatus which comprises an upright column, transverse partitions in said column forming a vertical series of chambers, gravity overflow connections between the chambers to lead oil downwardly through the chambers, said connections being arranged to provide a vapor space in the upper portion of each chamber, a condenser connected with each of said spaces and positioned in the preceding chamber, and means for conducting condensates formed in said condensers through chambers preceding the chamber in which the condensate is formed.

15. A distilling apparatus which comprises an upright column, transverse partitions in said column for forming a vertical series of separate chambers, gravity overflow connections between adjacent chambers to lead oil downwardly therethrough, a heating still, means for leading oil from the last chamber of the series to the still, a condenser mounted in each chamber, means for leading vapors formed in each chamber into the condensers in the preceding chambers, a vapor connec-

tion between the still and the condenser of the last chamber of the series, and means for conducting hot residue from the still through the chambers.

5 16. A distilling apparatus which comprises an upright column, transverse partitions in said column for forming a vertical series of separate chambers, gravity overflow connections between adjacent chambers to lead oil 10 downwardly therethrough, a heating still, means for leading oil from the last chamber of the series to said still, a condenser in each of said chambers in contact with the oil under treatment therein, means for conducting 15 vapors formed in one chamber directly into the condenser of a preceding chamber, and means for conducting residue from the still through the chambers in a path countercurrent to the path of the flow of oil there- 20 through.

17. A distilling apparatus which comprises an upright column, transverse partitions in said column for forming a vertical series of separate chambers, gravity overflow connections 25 between the chambers to lead oil downwardly therethrough, a heating still, means for leading oil from the last chamber of the series to said still, means for condensing oil fractions in said chambers, and means for 30 separately conducting residue from the still and fractions condensed in the chambers through the chambers in a path countercurrent to the path of the flow of oil there- 35 through.

18. A distilling apparatus which comprises a series of oil vaporizing chambers, means for leading oil in succession through the said 40 chambers, vapor condensers in said chambers, means for conducting vapors from one chamber into a condenser of a preceding chamber, means to conduct uncondensed vapors from the condenser into the oil in the same chamber, means for heating the oil leaving the last chamber of the series to any desired tem- 45 perature, means for conducting vapors from said heating means to said last chamber, and a condensate passage leading from the condenser of each chamber through the preceding chambers.

50 19. A distilling apparatus which comprises a series of oil vaporizing chambers, means for leading oil in succession through the chambers, a condenser unit mounted in the lower portion of each chamber and adapted to be 55 cooled by the oil therein, means for conducting vapors from one chamber into a condenser of a preceding chamber, means for heating the oil leaving the last chamber of the series to any desired temperature, means 60 for conducting vapors from said heating means to the last chamber of the series, a condensate passage leading from the condenser of each chamber through the preceding chamber, and means for varying the flow 65 of the condensate in passages in the chambers.

20. A distilling apparatus which comprises a series of oil vaporizing chambers, means for leading oil in succession through the chambers, condensers in the said chambers, means for conducting vapor from one chamber into 70 the condenser of a preceding chamber, means for heating oil leaving the last chamber of the series to any desired temperature, means for conducting vapors from said heating means to the last chamber of the series, condensate 75 coils for conducting condensates from said condensers through preceding chambers, and means for by-passing condensate around a portion of the length of a coil within the chambers.

21. A distilling apparatus which comprises a series of oil vaporizing chambers, means for leading oil in succession through the chambers, vapor condensers in the said chambers, means for conducting vapors from one chamber into a condenser of the preceding chamber, means for heating the oil leaving the last chamber of the series to any desired temperature, means for conducting vapor from said heating means to said last chamber, a condensate passage leading from the condenser of each chamber through the preceding chambers, means for placing the condenser under pressure, and a trap for introducing condensates from the condensers into their respective 95 passages.

22. A distilling apparatus which comprises an upright column, transverse partitions dividing said column into a series of chambers each having a vapor zone, means for leading oil through said chambers in succession, condensers in the said chambers, means to introduce gas into the lowermost chamber, means to conduct gas and vapor from the vapor zone in one chamber into the condenser of a chamber above it, means to distribute the gas and uncondensed vapor over the bottom of the chamber in which the condenser is located, and means to conduct the condensates formed in the chambers in separate passages 100 upwardly through the chambers above those in which the condensates are formed.

23. A distilling apparatus which comprises an upright column, transverse partitions dividing said column into a series of chambers each having a vapor zone, means for leading oil through the chambers in succession, a condenser in each chamber, a heating still, means to lead oil from the bottom chamber of the column to the still, means to introduce heated gas into the bottom of the still, means to conduct vapor and gas from the still into the condenser of the bottom chamber, means to conduct gas and vapor from the vapor zone of one chamber into the condenser of a chamber above it, means to distribute the gas and uncondensed vapor from a condenser over the bottom of the chamber in which the condenser is located, and means to conduct the condensate formed in the condensers in separate 115 120 125 130

passages upwardly through the chambers above those in which the condensates are formed.

24. A distilling apparatus which comprises an upright column, transverse partitions dividing said column into a series of chambers, gravity overflow means for leading oil from the top to the bottom of the column while maintaining a predetermined depth of oil in each chamber, a gas distributor mounted on the bottom of each chamber, a condenser unit mounted in each chamber and adapted to be cooled by the oil therein, means for introducing a heated gas into the distributor of the bottom chamber, means to conduct gas and vapor from each chamber into the condenser of the chamber above it, means to conduct gas from the condenser in each chamber into the distributor of that chamber, and means for collecting condensates separately from the condensers.

25. The process of fractionally distilling oils, which comprises passing oil through a series of distinct heating zones of progressively higher vaporizing temperatures, conducting a heated gas through the zones in a path countercurrent to the flow of oil therethrough, passing the vapors formed in each zone into heat transfer with the oil in the next preceding cooler zones whereby a series of condensates is produced and heating the oil being passed through the zones by the condensate produced in zones of higher temperature.

35 26. A process of fractional distillation and condensation of oil, which comprises flowing oil to be treated through a series of vaporizing chambers maintained at successively higher vaporizing temperatures, condensing

part of the vapors given off in each chamber by absorbing heat therefrom by indirect heat exchange with liquid oil in a chamber of lower temperature, isolating the condensate so formed, from the oil in the chamber of lower temperature, heating the oil flowing through the series of chambers by the condensed vapors from chambers later in the series, and varying the heat applied to said oil to control the boiling point of the vapors condensed in said chambers.

27. The process defined in claim 26 in which the vapors remaining uncondensed in a chamber of lower temperature are mingled with the vapors evolved from the oil in that chamber.

28. In the fractional distillation and condensation of oil, the process which comprises maintaining a series of bodies of oil at successively higher temperatures, heating the oil in certain of said bodies by indirect heat transfer with vapors and condensates from bodies of higher temperature while simultaneously condensing a portion of said vapors and bubbling the uncondensed portion of said vapors through the oil bodies being heated.

29. In a distilling apparatus, a vaporizing chamber, means for maintaining a body of liquid to be distilled in said chamber, means for heating the liquid in said chamber comprising independent means for bringing hot gases and liquids into heat exchange relation but out of contact with the liquid to be distilled and means for introducing a portion of said gases into said chamber from the gaseous heat exchange heating means.

In testimony whereof I affix my signature.

DAVID G. BRANDT.

CERTIFICATE OF CORRECTION.

Patent No. 1,713,255.

Granted May 14, 1929, to

DAVID G. BRANDT.

It is hereby certified that error appears in the printed specification of the above numbered patent requiring correction as follows: Page 5, line 62, claim 2, after the word "with" insert the words "a portion of"; and that the said Letters Patent should be read with this correction therein that the same may conform to the record of the case in the Patent Office.

Signed and sealed this 13th day of August, A. D. 1929.

M. J. Moore,
Acting Commissioner of Patents.
